US0D1108381S

(12) **United States Design Patent** (10) Patent No.: **US D1,108,381 S**
(45) Date of Patent: ** Jan. 6, 2026

(54) **FILLER BLOCK FOR SUBSTRATE PROCESSING APPARATUS**

(71) Applicant: **KOKUSAI ELECTRIC CORPORATION**, Tokyo (JP)

(72) Inventor: **Yusaku Okajima**, Toyama (JP)

(73) Assignee: **KOKUSAI ELECTRIC CORPORATION**, Tokyo (JP)

(**) Term: **15 Years**

(21) Appl. No.: **29/961,389**

(22) Filed: **Sep. 5, 2024**

(30) **Foreign Application Priority Data**

Mar. 8, 2024 (JP) ..... 2024-004871 D

(57) **CLAIM**

The ornamental design for a filler block for substrate processing apparatus as shown and described.

DESCRIPTION

FIG. 1 is a front, top and right side perspective view of a filler block for substrate processing apparatus showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a cross sectional view taken along line 8-8 in FIG. 2.

1 Claim, 5 Drawing Sheets

FIG. 1

FIG. 2

FIG. 3

FIG. 4

FIG. 5

FIG. 6

FIG. 7

FIG. 8
